Application June 26, 1944, Serial No. 542,140

12 Claims. (Cl. 48—53.3)

1

This invention relates to acetylene generators and more particularly to a generator adapted to provide a measured feed of the carbide to the water.

An important object is to provide an acetylene generator having but one exterior control and this is operated by a simple push-pull rod.

Another important object of the invention is to provide a particularly safe generator including automatic means to shut off the carbide feed, if the operator fails to do so.

Still another important object is to provide a generator of this kind provided with locking means which automatically locks all closures against removal while gas is under pressure in the generator, but which means automatically unlocks the closures upon absence of gas pressure.

A major object is to provide a diaphragm-operated means for automatically opening the pop-off valve should the latter become stuck.

Another major object is to provide a portable acetylene generator which has quick-acting means to seal off the carbide compartment from the water upon tipping over of the generator.

Still another important object is to provide an acetylene generator which automatically locks against feeding carbide, when the water therein freezes.

Other objects and advantages of the invention will be apparent during the course of the following detailed description of the invention, taken in connection with the accompanying drawings, forming a part of this specification, and in which drawings:

Fig. 1 is a vertical section of the novel generator.

Fig. 2 is a top plan view of the main carbide hopper thereof, removed, but normally disposed at the upper end of the generator.

Figs. 3 to 6 inclusive are horizontal sections of the generator, taken substantially upon their respective lines of Fig. 1.

Figs. 7 and 8 are enlarged fragmentary vertical sections of the generator, taken substantially upon their respective lines of Fig. 1.

Figs. 9, 10 and 11 are vertical sections through three diaphragms employed in the novel generator.

Fig. 12 is a fragmentary vertical section of the generator upon substantially the line 12—12 of Fig. 1.

Fig. 13 is a section, normal to the section of Fig. 12 but showing an oscillating actuator for a valve, in an abnormal position.

2

Fig. 14 is a fragmentary vertical section, showing a carbide feed valve in a closed position.

In the drawings, wherein for the purpose of illustration is shown a preferred embodiment of the invention and wherein similar reference characters designate corresponding parts throughout the several views, the letter A may generally designate the novel generator, including a main housing 15 enclosing a carbide hopper 16, a measuring receptacle or starter cup 17, a water reservoir 18, a popoff valve 19 and a conventional flashback 20.

The main housing 15 is so arranged that the carbide hopper 16 is uppermost, the starter cup 17 immediately below the hopper 16 and communicating therewith, and the water reservoir 18 below the starter cup 17, with a downwardly and inwardly sloping partition 21, above the reservoir 18, providing a splash guard 22 having a central opening defining a valve seat 23. Preferably, this seat is arranged to seat a valve, to be described, which is normally spaced from and below the seat. The seat 23 includes a substantially horizontal ring-shaped main seat portion 24 and a depending collar-like auxiliary seat portion 25 spaced from the interior periphery of the portion 24 and secured to the under side of the partition 21. The other openings into the housing walls will be described in connection with the several portions of the housing.

The carbide hopper 16 is provided with a drum-like, vertical wall 26, an upper horizontal wall 27, and a downwardly and inwardly sloping bottom wall or sump 28. Preferably, this wall 28 is detachable, since it may be provided with an outwardly-extending perforated flange 29 at its upper end, while the wall 26 may be provided with an outwardly-extending perforated flange 30 at its lower end, both flanges being carried by an outwardly-extending perforated flange 31 carried by the wall of the housing 15. Suitable securing members 32, as bolts and nuts may be provided to detachably secure the several flanges together and, of course, gaskets may be employed, if desired.

This bottom wall or sump 28 is provided with a centrally disposed valve seal 33 which may have a bevelled face, sloping outwardly and downwardly.

The upper wall 27 of the carbide hopper 16 is provided with a centrally disposed filler opening 34 having an upwardly-extending exteriorly screw threaded collar 35. The closure therefor will be subsequently described.

The vertical wall 26 of the hopper 16 may sup-

port conventional accessories, as a pressure gauge 36.

The measuring receptacle 17 is, of course, much smaller than the hopper 16 and includes, preferably, a cylindrical vertical wall 40 secured at its upper end to the bottom wall or sump 28 of the hopper 16, and a bottom wall or sump 41 having a centrally-disposed valve seat 42, which may have an outwardly and downwardly bevelled face, and the axes of the seats 33 and 42 are, preferably, concentric.

Below the partition 21, the reservoir 18 occupies the lowermost portion of the main housing 15 and the bottom of this reservoir provides a sump 43 from the lowermost portion of which leads a suitable conduit 44 opening into the reservoir at one end and extending exteriorly of the housing 15 at its other end, where it may terminate in a valve 45. The vertical wall 46 of the reservoir 18 may be inturned as at 47 at its lower end to provide a firm, flat base for the generator and raise the conduit 44 slightly above the bottom of the generator. This reservoir is provided, of course, with the conventional downwardly hanging, pivoted, agitator paddle 48 with exterior manipulating handle 49 therefor.

The vertical wall 46 extends upwardly to carry the partition 21 and may then slope inwardly as at 50 to meet the vertical wall 26 of the hopper 16 and end in the flange 31 mentioned.

A water level for the reservoir is indicated by a dot and dash line 51.

Now as for the novel safety operating means for the generator, there is provided but one exterior member necessary for manual regulation of the generator and this one member automatically aids in the regulation of other conditions arising during use of the generator. This member is, preferably, a single rod 55, extending exteriorly and interiorly of the housing 15 through a suitable opening in the wall 46. The axis of this opening intersects the vertical axis of the housing 16, and the axes of the valve seats 33 and 42. The transverse cross section of the rod 55 is shown as square in Fig. 7, but it may have other shapes. However, it is not rotatable, but is reciprocable. At its outer exterior end, the rod may have a suitable removable handle 56, spaced from a small housing 57 secured to the outer side of the wall 46 and which housing carries, at its upper end a freely vertically slidably latching pin 58 having an end within the housing 57 to engage the walls of a socket or keeper 59 in the upper face of the rod 55. The upper or outer end of the pin 58 may have a finger grip 60. It is apparent that, as the rod reciprocates, the pin 58 will drop by gravity into the keeper 59 and the rod will then remain stationary, but may be released from the keeper by manually drawing up on the pin.

After passing through the wall of the housing 15, the rod is operatively connected, in any approved way to the center of a flexible sheet diaphragm 61 carried by an open-ended diaphragm housing 62, with the diaphragm 61 over this open end, suitably secured thereto and normally urged outwardly by an expansion coil spring 61^a. The diaphragm housing 62 is supported by the main housing wall so that the diaphragm 61 faces inwardly, into the chamber 63, between the partition 21 and wall 28, and the structure 60 to 62 inclusive constitutes means to reciprocate the rod 55 upon changes in gas pressure within the housing 15. From this diaphragm 61 the rod extends into the chamber 63, and is provided with

six suitable stops such as fixed lugs 64—69, spaced along the rod. These lugs may be of any suitable shape and their function is to engage certain parts of the mechanism to be next described.

The lug 64 nearest the diaphragm 61 is adapted to engage the legs 70 of a lever 71 straddling the rod 55, as in Fig. 8, with the legs 70 occupying part of the space between the diaphragm 61 and lug 64. Since substantially similarly shaped levers engage the lugs 66 and 67, similar reference characters are employed for all three levers which are, inverted L-shaped with the normally vertical portion 72 of the lever 71 carrying the legs 70, the horizontal portion 73 providing an abutment.

The horizontal portion of the lever 71, the legs of which are engaged by the lug 64, abuts a vertical rod 74 which extends upwardly to contact the valve (not shown) of the popoff valve 19. Each lever 71 is pivoted at the juncture of the portions 72 and 73 by a pivot pin 75 journaled to the main housing walls. When the rod 55 moves toward the left, urged by the diaphragm 61, forced inwardly by undesirable gas pressure of seventeen pounds, the lug 64 will move the portion 72 to the left and the portion 73 in an arc upwardly, raising the rod 74 and forcing the valve of the popoff valve from its seat (in the event this valve sticks). Movement of the rod 55 to the right will cause the lever 71 to assume its normal position, with the portion 72 vertical, since the levers are balanced to assume such a normal position.

The lug 65 is adapted to contact a vertically slidable pin 75^a of a conventional thermostat 76 which is supported upon the partition 21 and this pin 75^a is adapted to move upwardly, urged by the thermostat mechanism, upon drop of temperature inside the housing 15 sufficient to freeze the surface of the water in the water reservoir. Since this lug 65 is to the right of the pin 75^a when the rod is moved inwardly, the rod cannot be pulled out to start the generation of gas, if this pin contacts the lug 65. Normally the free outer end of the pin 75^a is below the horizontal plane of the lug 65.

As for the lugs 66 and 67, these are associated with two levers 71 for operation of the valve at the base of the measuring receptacle 17. The lug 66 is to the left of the taller lever 71 and upon movement of the rod to the right, will cause the horizontal portion 73 of this taller lever 71 to move upwardly in an arc and cause a vertical valve stem attached to a conical valve 77 at its upper end, to move upwardly in the spider 78 secured to the wall of the receptacle 17, and almost fully seat on the valve seat 42. Of course, movement of the lug 66 in the other direction (toward the left) will operate to unseat the valve 77. However, movement of the rod 55 sufficiently to the left will also nearly seat this valve 77 (as when excessive gas pressure operates the diaphragm 61). In such an event, the last lever 71 (that is, the extreme right lever) will pivot, urged by the lug 67, which is to the right of this last lever 71, its normally horizontal arm 73 will contact the horizontal arm 73 of the adjacent lever and, the vertical portion of this adjacent lever, being free to move to the right, both levers will move to elevate their horizontal portions and nearly seat the valve 77. (This valve 77 seats sufficiently to prevent carbide from moving past the seat but not enough to prevent gas from flowing past the seat.) Both levers will drop, upon movement of the rod to the right. Thus, the lug

67, shorter lever 71, its pivot pin 75, lug 64, its associated lever 71 and its pivot pin 75 constitute means to operate the popoff valve and valve 71 upon operation of the diaphragm 61, but manual sliding movement of the rod to the right in Figure 1 will not affect these two levers 71.

The lug 68 is simply one to limit outward movement of the rod 55 and may engage an innermost support 80 for the rod 55, extending from any suitable housing structure wall.

The lug 69 is associated with means to close off the water reservoir 18 from the rest of the housing 15 and lock the mechanism upon tipping over or abnormal tilting of the housing 15. It has the additional function of locking the mechanism upon a drop in the water level and closing off the water reservoir at the same time.

The first of these safety features includes a normally vertical arm 81 having a suitable weight 82 at its lower end, a ball and socket pivot 83 intermediate its ends and an enlargement 84 at its upper end, with an upper face 85 and, preferably a conical, upwardly opening recess or concavity 86 in this face 85.

Normally contained in this recess 86 is a conical enlargement 87 depending from the intermediate portion of a lever or arm 88, pivoted at one end as at 89 and with its free end contacting the lower end of a vertical valve stem 90, carrying a valve 91, which preferably comprises a disc portion 92 and, above this disc portion an arcuate valve portion 92, having a curved lower face. This valve 91 seats upon the seat 23 when the arm 88 pivots upwardly and urges the valve stem 90 upwardly, since this arm 88 will swing upwardly or to a horizontal position upon different positions of the enlargement 87 with respect to the concavity 86. No matter in which direction the vertical arm 81 swings, except to a vertical position, the enlargement will change its position so as to be more or less outside the concavity and thus move the arm 88.

The valve stem 90 may extend upwardly through the valve 91 as a pin 95 to contact the lug 69 when the valve 91 is closed and prevent movement of the rod 55 but, when the valve 91 is unseated, the lug 69 is not interfered with by this pin 95.

There is provided a suitable float 96, as of cork, which floats upon the water level 51 and carries an upwardly-extending arm or rod 97 loosely slideable in bearings 98, having a normally horizontally-disposed float lever 99 pivoted as at 100 to its upper end. Intermediate its ends, this lever 99 is pivoted, as at 101 to a support 102 which may be carried by a suitable portion of the housing 15. The free end of this float lever 99 engages the under side of the arm 88, intermediate the end of the latter. By this arrangement, when the float 96 drops with drop in the water level 51, the arm 97 will move downward, the lever 99 will swing upwardly, swing the arm 88 upwardly seat the valve 91 and lock the operating mechanism as stated. No more carbide can then enter the reservoir 18 until the water level is corrected and the float 96 rises.

It is preferred to provide a diaphragm-operated valve 105 for the seat 33 at the lowermost portion of the lower wall 28 of the hopper 16. This valve 105 is normally disposed below the seat 33 and has an upwardly-extending stem 106 pivoted, as at 107, (shown particularly in Fig. 10) at its upper end in the hopper compartment, to the end of a short horizontal arm 108, which is, in turn, pivoted as at 109 at its other end to the exterior of a diaphragm housing 110

which carries a flexible sheet diaphragm 111 over its open end and to which is secured a depending arm 112 having an eye at its free end, embracing the intermediate portion of the short arm 108.

5 The housing 110 carries a suitable means urging the diaphragm 111 outwardly, as a weight 113. Thus upon the building up of gas pressure within the housing 15, the diaphragm will be forced inwardly and the operative connection 10 between it and the valve 105 will almost seat this valve, that is, will seat it enough so that no carbide can enter the measuring receptacle 17 to drop therethrough and into the water. When the gas pressure has dropped to normal, the diaphragm, urged by the weight 113, will move outwardly and cause the valve 105 to unseat. The diaphragm housing 110 may be supported by a bracket 114 carried by a suitable portion of the main housing structure.

20 In Fig. 9 is illustrated one of the two closure latching means. This one is particularly adapted for a closure 115 for the carbide receiving opening 34 at the top of the housing 15. This closure 115 is a cap having a depending skirt provided with interior screw threads and, extending through the center of the cap, is a thumb screw 116 with its inner end bearing against the upper face of a suitable sealing disc 117 resting upon the collar 35. Extending outwardly from the outer periphery of the skirt are spaced apart wings or lugs 118. Preferably there are 4 such lugs 118, spaced 90° apart.

25 The means of Fig. 9 includes a diaphragm structure providing an open ended housing 120 closed at its open end by a thin flat sheet diaphragm 121 to the interior face of which is attached a pin 122 slideable vertically through the closed end wall of the housing 120 and through the upper wall 27 of the hopper 16 to extend outwardly of the latter closely adjacent closure 115. The position of this pin 122 is such that, when the generator is not operating, and the gas pressure has subsided, the top of the pin 122 is below the horizontal planes of the bottoms of all the lugs or wings 118 but when the pressure builds up, the diaphragm 121 will be forced inwardly against the pressure of the coil expansion spring 123 and the pin 122 will rise and its upper end extend above these horizontal planes, whereby the pin end will function as a stop to prevent 30 more than a quarter turn of the closure 115. When the gas becomes exhausted as by exhaustion of the carbide supply, the pin will move downwardly, as the spring 123 urges the diaphragm 121 downwardly and the closure 115 may 35 be unscrewed.

40 The diaphragm shown in Fig. 11 is one employed with the closure 125 to the water intake. This closure 125 is a screw-cap with wings or lugs 126 disposed as are the wings or lugs 118, and 45 adapted to close the L-shaped intake pipe 27.

45 This diaphragm structure includes an open-ended housing 130, a flexible sheet diaphragm 131 therefor with the diaphragm facing inwardly of the housing 15, and a pin 132 secured to the inner face of the diaphragm 131. This pin extends through the closed end wall 132 of the housing 130 and through the wall 46 of the housing 15 in position to contact the lugs or wings 126 of the closure 125 but, as may be 50 seen in Fig. 1, the free end of the pin 131 is outwardly of the vertical planes of the lugs 126 when the diaphragm is straight, but moves within these planes. When gas pressure forces 55 the diaphragm inwardly a conventional expan-

sion coil spring 133 bears against the diaphragm structure and wall 132.

A suitable tube 135 opens at one end in the housing 15 and extends to the flashback 20, as is well known in the art.

It will be seen, from the foregoing, that a particularly safe generator is provided with a single manual feed control and automatic regulation of the control governed by gas pressure within the generator, with drop in water level and temperature as well as abnormal position of the generator, affecting this control. The generator is also rendered safe by the provision of the diaphragm-operated devices for preventing removal of the closures while the generator is under gas pressure.

With the generator empty, the valve 77 at the lower end of the starter cup 17 seated and the rod 55 in a position with the pin 58 in the recess 59, the closures may be removed, the hopper 16 charged with carbide and the reservoir 18 filled with water so that the float 96 rises and unseats the valve 91. As carbide enters the hopper 16 some will pass to the starter cup 17 and remain there since the valve 77 is seated. Now, upon manually raising the pin 58 from the recess 59 and pulling out on the rod 55, the valve 77 will unseat, the carbide in the starter cup 17 will drop to the water, gas will begin to form and the diaphragms 121 and 131 will function to latch the closures against removal. While the gas remains at a desired pressure there will be no action of the diaphragm 111 but, if this pressure begins to rise this diaphragm will almost seat the valve 105 preventing further feeding of carbide until the pressure drops to normal. Since the valve 105 seats only enough to prevent feeding of carbide, but not enough to prevent gas from entering the hopper 16, upon the subsequent drop in gas pressure, the diaphragm 111 will again function to unseat valve 105. Of course, it is apparent that various changes in pressure will affect the diaphragm 111 accordingly and the extent valve 105 seats and unseats will also vary accordingly.

If the carbide hopper becomes empty, diaphragm 61 will function to slide rod 55 to the right and seat valve 77 as valve 105 unseats. At the same time the drop in pressure will cause the closure latching mechanism to function to unlatch the closure so that the carbide and water supplies may be replenished, some of the carbide running down into the starter cup again.

Various changes may be made to the form of the invention herein shown and described without departing from the spirit of the invention or scope of the claims.

I claim:

1. In an acetylene generator, a housing provided with a carbide hopper and a water reservoir, a measuring receptacle below said hopper, communicating therewith and provided with a valve seat at its lower end; a valve for said seat, having a depending stem; a control rod slidably carried substantially horizontally by said housing, with one end exteriorly thereof, the other end interiorly thereof, and the vertical axis of said stem intersecting said rod; an inverted, substantially L-shaped lever pivotally carried by said housing, with the free end of the normally horizontal arm of said lever below and closely adjacent the lower end of said stem, and the normally vertical arm of said lever straddling said rod; and an abutment on said rod contacting said normally vertical arm.

2. In an acetylene generator, a housing provided with a carbide hopper and a water reservoir, a measuring receptacle below said hopper, communicating therewith and provided with a valve seat at its lower end; a valve for said seat, having a depending stem; a control rod slidably carried substantially horizontally by said housing, with one end exteriorly thereof, the other end interiorly thereof, and the vertical axis of said stem intersecting said rod; means within said housing, operatively connected with said rod to reciprocate said rod upon changes in gas pressure with said housing; an inverted, substantially L-shaped lever pivotally carried by said housing, with the free end of the normally horizontal arm of said lever below and closely adjacent the lower end of said stem, and the normally vertical arm of said lever straddling said rod; a second inverted, substantially L-shaped lever pivotally carried by said housing with the free end of the normally horizontal arm of said second lever directly below and closely adjacent said first-named free end, and the normally vertical arm of said second lever straddling said rod, said levers being disposed so that their said free ends extend forward toward each other; and a pair of fixed abutments on said rod, one contacting one face of one normally vertical arm and the other contacting the opposite face of the other normally vertical arm.

3. In an acetylene generator, a housing provided with a carbide hopper and a water reservoir, a measuring receptacle below said hopper, communicating therewith and provided with a valve seat at its lower end; a valve for said seat, having a depending stem; a control rod slidably carried substantially horizontally by said housing, with one end exteriorly thereof, the other end interiorly thereof, and the vertical axis of said stem intersecting said rod; means within said housing, operatively connected with said rod to reciprocate said rod upon changes in gas pressure with said housing; an inverted, substantially L-shaped lever pivotally carried by said housing, with the free end of the normally horizontal arm of said lever below and closely adjacent the lower end of said stem, and the normally vertical arm of said lever straddling said rod; a second inverted, substantially L-shaped lever pivotally carried by said housing with the free end of the normally horizontal arm of said second lever directly below and closely adjacent said first-named free end, and the normally vertical arm of said second lever straddling said rod, said levers being disposed so that their said free ends extend toward each other; and a pair of fixed abutments on said rod, one contacting one face of one normally vertical arm and the other contacting the opposite face of the other normally vertical arm.

4. In an acetylene generator, a housing provided with a carbide hopper and a water reservoir, a measuring receptacle below said hopper and above said reservoir, communicating with both, and provided with a valve seat at its lower end; a valve for said seat; a control rod slidably carried by said housing and extending interiorly and exteriorly thereof; means operatively connected with said rod to reciprocate said rod upon changes in gas pressure within said housing; a pop-off valve; means carried by said rod and housing to operate said first named valve upon manual sliding movement of said rod in one direction; and means carried by said rod and housing to operate said valves upon operation of said first means to slide said rod in one direction and to

remain inoperative during operation of said second means.

5. In an acetylene generator, a housing provided with a carbide hopper and a water reservoir, a measuring receptacle below said hopper and above said reservoir, communicating with both, and provided with a valve seat at its lower end; a valve for said seat; a control rod slidably carried by said housing and extending interiorly and exteriorly thereof; means operatively connected with said rod to reciprocate said rod upon changes in gas pressure within said housing; a pop-off valve; means carried by said rod and housing to operate said first named valve upon manual sliding movement of said rod in one direction; and means carried by said rod and housing to operate said valves and said second means upon operation of said first means to slide said rod in one direction and to remain inoperative during operation of said second means.

6. In a portable acetylene generator a housing provided with a carbide hopper, a water reservoir and a partition between said hopper and reservoir, said partition having a valve seat; a measuring receptacle below said hopper and above said reservoir and partition, communicating with said hopper and provided with a valve seat at its lower end; a valve for said second seat; a control rod slidably carried by said housing and extending interiorly and exteriorly thereof; means carried by said rod and housing to operate said valve upon reciprocation of said rod; a valve for said first seat; safety means carried by said housing to close said last named valve upon tipping of said housing; and means associated with said safety means to restrain said rod against movement upon operation of said safety means to close said last named valve.

7. In a portable acetylene generator a housing provided with a carbide hopper, a water reservoir and a partition between said hopper and reservoir, said partition having a valve seat; a measuring receptacle below said hopper and above said reservoir and partition, communicating with said hopper and provided with a valve seat at its lower end; a valve for said second seat; a control rod slidably carried by said housing and extending interiorly and exteriorly thereof; means carried by said rod and housing to operate said valve upon reciprocation of said rod; a valve for said first seat; safety means carried by said housing to close said last named valve upon tipping of said housing; and means, carried by said rod and associated with said safety means carried by said rod to restrain said safety means to close said last named valve.

8. In a portable acetylene generator a housing provided with a carbide hopper, a water reservoir and a partition between said hopper and reservoir, said partition having a valve seat; a measuring receptacle below said hopper and above said reservoir and partition, communicating with said hopper and provided with a valve seat at its lower end; a valve for said second seat; a control rod slidably carried by said housing and extending interiorly and exteriorly thereof; means carried by said rod and housing to operate said valve upon reciprocation of said rod; a valve for said first seat; safety means carried by said housing to close said last named valve upon tipping of said housing; and means, carried by said rod and associated with said safety means carried by said rod to restrain said safety means to close said last named valve and to remain inoperative during normal operation of said generator.

9. In a portable acetylene generator a housing provided with a carbide hopper, a water reservoir and a partition between said hopper and reservoir, said partition having a valve seat; a measuring receptacle below said hopper and above said reservoir and partition, communicating with said hopper and provided with a valve seat at its lower end; a valve for said second seat; a control rod slidably carried by said housing and extending interiorly and exteriorly thereof; means carried by said rod and housing to operate said valve upon reciprocation of said rod; a valve for said first seat; safety means carried by said housing to close said last named valve upon tipping of said housing and upon depletion of water in said reservoir; and means associated with said safety means to restrain said rod against movement upon operation of said safety means to close said last named valve.

10. In a portable acetylene generator a housing provided with a carbide hopper, a water reservoir and a partition between said hopper and reservoir, said partition having a valve seat; a measuring receptacle below said hopper and above said reservoir and partition, communicating with said hopper and provided with a valve seat at its lower end; a valve for said second seat; a control rod slidably carried by said housing and extending interiorly and exteriorly thereof; means carried by said rod and housing to operate said valve upon reciprocation of said rod; a valve for said first seat; safety means carried by said housing to close said last named valve upon tipping of said housing; and means associated with said safety means to restrain said rod against movement upon operation of said safety means to close said last named valve; said safety means including a normally vertical weighted rod, a ball-and-socket pivot for said rod; an enlargement upon the upper end of said weighted rod, providing a flat, normally horizontally disposed face, a normally horizontal arm, a pivot for said last named arm, with the free end portion of said last named arm resting upon said face, a vertically-disposed stem for said last named valve, with the lower end of said stem contacting the free end of said last named arm, a second stem extending from said last named valve toward said first named rod and a stop upon said first named rod and disposed so that the side of said stop will contact said last named stem upon closing said last named valve.

11. In a portable acetylene generator a housing provided with a carbide hopper, a water reservoir and a partition between said hopper and reservoir, said partition having a valve seat; a measuring receptacle below said hopper and above said reservoir and partition, communicating with said hopper and provided with a valve seat at its lower end; a valve for said second seat; a control rod slidably carried by said housing and extending interiorly and exteriorly thereof; means carried by said rod and housing to operate said valve upon reciprocation of said rod; a valve for said first seat; safety means carried by said housing to close said last named valve upon tipping of said housing; and means associated with said safety means to restrain said rod against movement upon operation of said safety means to close said last named valve, said safety means including a normally vertical weighted rod, a ball-and-socket pivot for said rod, an enlargement upon the upper end of said weighted rod, providing a flat, normally horizontally disposed face and a concavity inwardly of said face,

11

a normally horizontal arm, a pivot for said last named arm, with the free end portion of said last named arm resting upon said face, said last named arm having a depending enlargement, normally disposed within said concavity, a vertically-disposed stem for said last named valve, with the lower end of said stem contacting the free end of said last named arm, a second stem extending from said last named valve toward said first named rod and a stop upon said rod and disposed so that the side of said stop will contact said last named stem upon closing said last named valve.

12. In a portable acetylene generator a housing provided with a carbide hopper, a water reservoir and a partition between said hopper and reservoir, said partition having a valve seat; a measuring receptacle below said hopper and above said reservoir and partition, communicating with said hopper and provided with a valve seat at its lower end; a valve for said second seat; a control rod slidably carried by said housing and extending interiorly and exteriorly thereof; means carried by said rod and housing to operate said valve upon reciprocation of said rod; a valve for said first seat; safety means carried by said housing to close said last named valve upon tipping of said housing; and means associated with said safety means to restrain said rod against move-

12

ment upon operation of said safety means to close said last named valve; said safety means including a normally vertical weighted rod, a ball-and-socket pivot for said rod; an enlargement upon the upper end of said weighted rod providing a flat, normally horizontally disposed face, a normally horizontal arm, a pivot for said last named arm, with the free end portion of said last named arm resting upon said face, a vertically-disposed stem for said last named valve, with the lower end of said stem contacting the free end of said last named arm, a second stem extending from said last named valve toward said first-named rod, a stop upon said rod and disposed so that the side of said stop will contact said last named stem upon closing said last named valve, a float, a vertically reciprocating rod extending upwardly from said float, means loosely retaining said last named rod in substantially upright position for reciprocation thereof, a lever, a pivot at one end thereof adjacent the upper end of said last-named rod, and a pivot for said last named rod, inwardly of the other end thereof, said other end of said last named rod extending directly beneath said normally horizontal arm, whereby as said float descends, said last named rod will move and raise said normally horizontal arm.
